UNITED STATES PATENT OFFICE.

THADDEUS S. GRIMES, OF COLUMBUS, GEORGIA, ASSIGNOR TO LUMMUS COTTON GIN COMPANY, OF COLUMBUS, GEORGIA, A CORPORATION OF GEORGIA.

MEANS FOR OPERATING THE DOGS OF A BALING-PRESS.

1,189,095.

Specification of Letters Patent. Patented June 27, 1916.

Application filed July 27, 1915. Serial No. 42,204.

To all whom it may concern:

Be it known that I, THADDEUS S. GRIMES, a citizen of the United States, residing at Columbus, in the county of Muscogee and State of Georgia, have invented certain new and useful Improvements in Means for Operating the Dogs of a Baling-Press; and I do hereby declare the following to be a full, clear, and exact description of the invention, such as will enable others skilled in the art to which it appertains to make and use the same.

This invention relates to means for operating the dogs of a baling press, and more specifically to means for releasing the dogs automatically when the position of the press box is shifted for packing the bale.

The invention consists in the provision of novel means for mounting the dogs, the latter being constructed to accomplish effectively the purpose for which they are intended, and in the provision of novel means, which may include a collar mounted on the central vertical column of the press and a reciprocable member engaged by the collar for releasing a rock shaft upon which the dogs are pivotally mounted.

The invention also consists in other novel structures hereinafter described.

In the accompanying drawings, Figure 1 is a view in side elevation; Fig. 2 is an elevation of one of the press boxes showing the mechanism for operating the dogs, one of the doors being open; Fig. 3 is a similar elevation showing both doors closed and the dogs in operative position; Fig. 4 is a horizontal section through the press boxes, with a plan view of the mechanism for operating the dogs; Figs. 5 to 8 are views of details of construction described below. Fig. 9 shows a modification having to do with the operation of the dogs.

In the several views of the drawing the press boxes are indicated by 10 and 12, and the vertical central column about which the boxes revolve is designated 15; the central strain rod of the press is shown at 16. The column 15 carries a collar 17 having an upper flange 18 and a lower flange 19 provided with cut-away portions 20, 21 oppositely located, for the purpose specified below.

Brackets 25 are carried on member 27 of the press structure, these brackets being de-

signed to furnish bearings for reciprocating bars 30 each located between the aforesaid collar and one of the crank shafts 34. Members 30 carry brackets 36 in which rollers 37 are journaled as shown in Fig. 5, the rollers bearing against the respective flanges of collar 17. Outturned portions 38 constitute handles and afford means for engagement by cranks 40 carried by shafts 34.

Each door carries brackets 45 provided with arc-shaped slots 46 through which the crank shafts extend. The dogs are loosely mounted on these shafts and are so shaped and balanced that they normally assume the position shown in Fig. 3 when the doors are closed and the shafts are locked, but when the trumper is forcing the cotton downward, the ends 48 of the dogs move toward the wall of the press box, as shown by the dotted line. The dogs are indicated by 47, and it may here be stated that they project approximately six inches into the boxes.

Each slotted bracket 45 has an arc-shaped rack portion 49 engaged by a pinion 50 carried by the crank shaft. The position of the pinion and shaft when the dogs are in operative position is shown in Fig. 3, and the position when the doors are down is shown in Fig. 2.

Each reciprocating bar is provided with a flattened portion 51 for engaging the crank of the adjacent shaft, and each of the said bars carries a collar 52 engaging a portion of bracket 25, for limiting the rotary movement of the bar and holding the member 38 at its end in a horizontal position, either to the right or to the left. Portion 53 of bracket 25 is inclined at the sides for engagement by the wing portion 54 of collar 52. When either reciprocating bar moves toward the center of the press for releasing the dogs, wing portion 54 engages the inclined portion at 53 and causes member 38 to turn upwardly and out of engagement with the adjacent crank shaft, thereby insuring the positive and automatic release of the dogs. The shifting of the position of the press boxes brings rollers 37 opposite the flat surfaces of cam members 18 and 19, and bars 30, 31 then move toward the center column, as stated, owing to the strain to which they are subjected.

In order to lock the dogs in place, the crank shaft on each side is rotated by means

of its handle, causing the pinions to engage the arc-shaped racks of brackets 45. Bars 30 are then rotated manually through approximately 90 degrees and caused to engage their corresponding crank shafts, thereby holding the latter and the dogs in operative position, with rollers 37 bearing against the flanges of the central collar. The locking device operates only on the tramping side of the press. If the dogs are not locked at the beginning of the tramping operation they can be locked at any time desired.

I do not wish to be limited to the details of construction shown and described, but 15 may make such changes and alterations as fall within the scope of the appended claims.

In Fig. 9 a strip 60 on the side of the door of the press box engages and holds the dogs out of the box in the manner shown, when 20 the crank shaft moves downwardly for releasing the dogs. The movement of the dogs during the tramping operation is not interfered with.

What I claim is—

25 1. In a device of the class described, a dog, means for mounting the dog, means for retaining the dog in operative position, including a plurality of rotatable members having their axes at an angle and adapted 30 to engage in one position, and means for automatically releasing the dog.

2. In a device of the class described, a dog, means including a member having an arc-shaped slot for mounting the dog permitting the pivotal movement thereof in a 35 plurality of positions, and means for automatically releasing the dog.

3. In a device of the class described, a dog, means including rack and pinion mechanism for mounting the dog, and means for 40 automatically controlling the dog.

4. In a device of the class described, a dog, mounting means therefor, and means including a cam member and a reciprocable 45 member for controlling the dog, a press box into which the dog projects, and a stationary member adjacent to the box and carrying the cam member.

5. In a device of the class described, a 50 dog, mounting means therefor including a rock shaft movable in a direction transversely of the axis of the shaft, means for retaining the shaft, a stationary member,

and means coöperating therewith for automatically releasing the retaining means. 55

6. In a device of the class described, a press box, a rock shaft mounted thereon, a dog loosely mounted on the shaft, rack and pinion mechanism for varying the position of the shaft, a stationary member and a cam member carried thereby, and a reciprocating member coöperating with the cam member and rock shaft. 60

7. In a device of the class described, a pivotally mounted dog, means for shifting the pivotal mounting of the dog, said means including a rock shaft, means arranged to be partly rotated for engaging and retaining the shaft, and means for automatically producing partial rotation for releasing the 70 shaft. 75

8. In a device of the class described, a pivotally mounted dog, means for shifting the pivotal mounting of the dog, said means including a rock shaft, reciprocable means 75 arranged to be partly rotated manually for engaging and retaining the shaft, and means for automatically producing partial rotation for releasing the shaft.

9. In a device of the class described, a stationary member, a press box arranged to be rotated with reference to said member, a dog pivotally mounted in the box, a slotted bracket provided with a toothed rack, a rock shaft, a pinion carried by the shaft for 80 engaging the rack, a dog mounted loosely on the shaft, means coöperating with the rock shaft and the stationary member for retaining the shaft in a given position and for releasing the latter upon changing the 85 position of the box. 90

10. In a device of the class described, a dog, means including rack and pinion mechanism for mounting the dog, means for automatically controlling the dog, and a press 95 box, the aforesaid mounting means permitting approximately one-half of the body portion of the dog to project into the press box.

In testimony whereof I affix my signature 100 in presence of two witnesses.

THADDEUS S. GRIMES.
